CLAIM

I claim the ornamental design for an aperture insert component, as shown and described.

DESCRIPTION

FIG. 1 is a top perspective view of an aperture insert component showing the claimed design;

FIG. 2 is a bottom perspective view of the claimed design of FIG. 1;

FIG. 3 is a top view of the claimed design of FIG. 1;

FIG. 4 is a bottom view of the claimed design of FIG. 1;

FIG. 5 is a left side view of the claimed design of FIG. 1, the right side view of the claimed design of FIG. 1 being a mirror image thereof; and,

FIG. 6 is a front view of the claimed design of FIG. 1, the rear view of the claimed design of FIG. 1 being a mirror image thereof.

The evenly dashed broken lines shown in the figures depict portions of the aperture insert component that form no part of the claimed design.
